EUGENE SIMON, OF OTTAWA, ONTARIO, CANADA.

BUNDLE-TYING MACHINE.

1,332,523.

Specification of Letters Patent. Patented Mar. 2, 1920.

Application filed March 17, 1919. Serial No. 263,281.

To all whom it may concern:

Be it known that I, EUGENE SIMON, a subject of the King of Great Britain, and resident of the city of Ottawa, in the Province of Ontario, Dominion of Canada, have invented certain new and useful Improvements in Bundle-Tying Machines, of which the following is a specification.

This invention relates to improvements in bundle tying machine and the objects of the invention are to provide a simple and effective means for tying a bundle of boards or the like with wire and severing the wire after the knot has been formed therein. Further objects of the invention are to enable the various operations to be performed automatically and with a maximum degree of safety to the operator. Further objects are generally to improve and simplify the construction of the device and to enable the various working parts to better perform the functions required of them, and it consists essentially of the improved construction hereinafter described in detail in the accompanying specification and drawings.

In the drawings:

Figure 1 is a side elevation of an embodiment of the invention.

Fig. 2 is an end view.

Fig. 3 is a plan view.

Fig. 4 is a perspective detail of the controlling lever.

Fig. 5 is a perspective detail of the knotting mechanism.

Fig. 6 is a sectional view through the knotting mechanism.

Fig. 7 is a perspective view of the knotting and cutting disks.

Fig. 8 is a plan view of one of the gears of the knotting device.

Fig. 9 is a plan view of one of the disks of the knotting mechanism.

Fig. 10 is a detail showing a sectional plan of the wire cutting mechanism.

In the drawings like characters of reference indicate corresponding parts in all the figures.

Referring to the drawings, A represents a frame of suitable construction to support the various working parts. B and C represent reels of wire mounted on a cross shaft 10; I have shown two reels but it will be seen that as many as are desired may be used, the operating parts being duplicated for each reel. The shaft 10 is driven with belts 11 and 12 extending from pulleys 13

and 14 on the shaft 10 to pulleys 15 and 16 on the countershaft 17 which itself is driven from a pulley 18. The belts 11 and 12 are ordinarily sufficiently slack to prevent turning of the shaft 10 which is only turned when it is desired to take up the slack in the wire and this is caused to take place by a belt tightening device and control lever comprising a cross shaft 20 having rollers 21 and 22 running on the belts 11 and 12, the cross shaft 20 being supported from pivoted levers 23 and 24, being adapted to be swung to and from the belts by means of a connecting bracket 25 which is pivoted to a lever 26, which lever is centrally attached to the frame and its opposite end connected by a connecting base 27 with a controlling lever 28, the lower extremity of which is pivoted to a bracket 29, the frame member 75 being adapted to be held in normal position by means of a catch bracket 30 on the frame, from which it may be disengaged by swinging it a short distance laterally. The wire on each of the reels B and C extends forwardly and extends through the central perforations 30^a and 31 in a two part spindle 33 respectively. The wire, after extending around the bundle D passes through a slot 34 in a rotatable disk 35 and through the slot 36 in the gear 32. The disk 35 is rotatably mounted in a semicircular recess 37 formed in the plate 38 extending vertically on the frame being held in such recess by means of removable bearing plates 39 and 40 which are bolted to the plate 38 and have a slot 41 between them through which wire may be inserted. To keep the disk 35 in place laterally it is formed with a plurality of peripheral annular projections 42 which fit corresponding tongues or grooves 43 in the plate 38 Fig. 6 and in the bearing members, and the disk 35 is caused to turn with the gear 32 by means of a bolt 44, which forms a pivotal connection between the disk 35 and the gear 32.

In order to effect cutting of the wire, the disk is pivoted with a stud 45 which fits a slot 46 on the gear while the bolt 44 extends through the perforation 47 in the gear and 105 corresponds to the perforation 48 in the disk. The disk is adapted to be supported and held in alined position with respect to the gear by means of a spring 46^a adapted to fit in a groove 46^b and bear against the pin 45. The 110 spindle 33 is formed in two parts 53 and 54, Fig. 6 one of which moves with a gear 32

and the other with a disk 35, the abutting surfaces of the parts being designed to shear the wire. The boards to be assembled into the bundle D are during assembly supported 5 on a suitable assembly table or platform E supported on the frame, which table has spaced cross bars 55 by which the bundles D are supported in such a way that the wire may be readily slipped beneath the same.

10 The gears 32 are driven from gears 56 mounted on pins 57 supported from the plate 38, the gears 56 having pulleys 58 connected and turning therewith, from which pulleys, belts 59 extend to pulleys 60 on countershafts 61 and 62, the countershafts being connected together by means of a chain 63 engaging sprockets 64 and 65 on the shafts. Shaft 62 is adapted to be driven from a suitable driving shaft 17 driven by 15 the pulley 18 connected to the shaft 62 by means of a bevel gear 68 designed to engage either one of the pinions 69 or 70 on the shaft 62, the shaft being designed to be moved longitudinally and designed to engage 20 either gear, the longitudinal movement being effected by means of a pivoted hand lever 71 which is provided with an arm 72 engaging a collar 73 on the shaft designed to rotate on the shaft and not move 25 longitudinally thereon.

The belts 59 are normally kept tight by means of rollers 80 carried on pivoted levers 81 and held against the belt by means of springs 82 extending from the arms 81 to the 30 frame.

In the operation of the invention the wire is drawn from the reel B or C and threaded by hand through the central perforation 31 then wound around the bundle D and the 35 free end placed loosely in the slots formed in the upper part of the spindle 33. The lever 71 is actuated to drive the gears 32 which will twist one portion of the wire carried in the slot about the portion extending through the central perforation causing a knot to be made. About three revolutions will be sufficient; when these revolutions have been accomplished the operator reverses the lever for a moment causing the 40 gear 60 to engage with the opposite pinions 70 or 69. On the reverse operation the disk 35 is engaged by the spring controlled dog 49 and held against turning and the gear 32 will pivot about the pin 44 while the 45 stud 45 moves in the slot 46, this will cause the slot in the gear to move out of alignment with the slot in the disk against the spring 46^a, causing the shearing action of the strand of wire which is located in the slot. This 50 change in position of the gear and disk is only temporary and the disk will again be brought into alignment again by means of spring 46^a. The turning in a reverse direction is stopped by means of a reciprocable 55 spring dog 49 which fits in a groove 50 and

is held against the disk by springs 52, the dog being adapted to engage a projection 52^a on the disk when turning in the reverse direction. When it is desired to take up the slack in the wire the lever 28 may be operated as already explained. The gear 32 never actually becomes unmeshed from the gear 56 but of course the meshing is not so deep during the cutting of the wire, this being due to the pivotal action of the gear 32. 75 There is nothing to prevent the gear 32 returning to its normal position relatively to the gear 56 and meshing to the desired depth therewith.

It will be seen that this present invention 80 provides a simple and effective means by which an operator may quickly knot and cut the binding wire about a bundle of slat boards or the like and thus the necessity for the manual formation of the knot or cutting 85 of the wire is done away with.

What I claim as my invention is:

1. In a bundle tier, in combination, a gear, a disk pivoted to the gear having limited motion in respect thereto, said gear and said 90 disk each having a radial slot, a spindle formed in two parts extending through the gear and disk formed with a central perforation, means for driving the gear, and means for supporting the disk operatively in position.

2. In a bundle tier, in combination, a gear, a disk pivoted to the gear having limited motion in respect thereto, said gear and said 10 disk each having a radial slot, a spindle extending through the gear and disk formed with a central perforation, means for driving the gear, means for supporting the disk operatively in position, a spring dog, and means on the disk adapted to be engaged by 10 the spring dog, to bring the slot in the same in alignment with the slot on the gear.

3. In a bundle tying device, in combination, a knot tying and cutting mechanism comprising two rotating members having 11 movement relative to each other, adapted when moved relative to each other to cut the wire and when rotated together to form a knot in the wire, and means for driving said members, a wire reel, a belt drive for the 11 wire reel, and a belt tightening device adapted to tighten the belt.

4. In a bundle tier, a knotting and cutting device comprising a two part spindle having a central perforation, means for rotating 1 both parts of the spindle, and means for moving one part of the spindle transversely with respect to the other part.

5. A bundle tying device comprising, in combination, a frame, a table on the frame, 1 a plate extending upwardly from the table having a circular recess, a disk rotatably mounted in the recess, bearing plates holding the disk in the recess, said disk being formed with a radial slot, a gear formed 1

with a radial slot eccentrically pivoted to the disk, a two part spindle having one part in the gear and one part in the disk having a central perforation in both, means for limiting the movement of the disk with respect to the gear, and reversible driving means for the gear.

6. A bundle tying device comprising, in combination, a frame, a table on the frame, 10 a plate extending upwardly from the table having a circular recess, a disk rotatably mounted in the recess, bearing plates holding the disk in the recess, said disk being formed with a radial slot, a gear formed 15 with a radial slot eccentrically pivoted to

the disk, a two part spindle having one part in the gear and one part in the disk having a central perforation in both parts, means for limiting the movement of the disk with respect to the gear, driving means for the 20 gear, and a plurality of spaced supports on the table in position to support a bundle thereon.

In witness whereof I have hereunto set my hand in the presence of two witnesses.

EUGENE SIMON.
